NAPKIN OR THE LIKE

Vera Way Marghab, % Emile Marghab, Inc.,
250 W. 57th St., New York, N.Y.

Filed Jan. 8, 1964, Ser. No. 78,129

Term of patent 14 years

(Cl. D92—26)

The single figure is a plan view of a napkin or the like of conventional thickness showing my new design.

The essential feature of the invention resides in the particular stylized design and arrangement of zebra and its stripes against a contrasting background on a napkin trimmed by a scalloped edge matching the dark zebra stripes.

I claim:

The ornamental design for a napkin or the like, substantially as shown and described.
